(57) **CLAIM**

The ornamental design for a data capture and recording device, as shown and described.

DESCRIPTION

FIG. 1 is a rear perspective view of a data capture and recording device for illustrating my new design;

FIG. 2 is a side view thereof;

FIG. 3 is an opposite side view thereof;

FIG. 4 is a front view thereof;

FIG. 5 is a rear view thereof;

FIG. 6 is a top view thereof; and,

FIG. 7 is a bottom view thereof.

The broken line showing the otoscope in FIG. 2 is included to indicate environmental structure and forms no part of the claimed design. The additional broken lines represent portions of the data capture and recording device that form no part of the claim.
